THREAD EXTRACTING, CLAMPING, AND CUTTING DEVICE FOR LOOMS

George F. Bahan, Greenville, S. C.

Application September 23, 1949, Serial No. 117,378

11 Claims. (Cl. 139—260)

1
This invention relates to looms and more especially to an improved thread clamping and cutting device for looms of the type having automatic bobbin transfer apparatus thereon.

In looms of a type having automatic quill or bobbin transfer apparatus associated therewith, it is necessary immediately prior to the filling thread being exhausted from a bobbin in a shuttle, to actuate certain mechanisms to cause the bobbin in the shuttle of the loom to be expelled from the shuttle as it is replaced by another, by means of the usual automatic filling replenishing apparatus. The present invention is concerned with an improved means for withdrawing the filling from a bobbin in a boxed shuttle in the shuttle box and for clamping and severing the filling thread immediately prior to this particular bobbin being replaced by another by a replenishing operation, to thereby avoid the accumulation of so-called loose ends and to prevent loose ends from being carried back into the warp at the selvedge of the cloth which, if not avoided, would produce defective cloth.

It is a primary object of this invention to provide an improved filling thread clamping and cutting device having a thread extracting bar which is adapted to be moved automatically into an engaging or operative position upon exhaustion of a spent filling thread, which bar will engage and ensnare the spent filling thread, through an opening in the shuttle box front, upon a beat-up stroke of the lay. Means are provided which are engageable by the lay for automatically releasing the spring loaded thread extracting bar to permit the same to withdraw very suddenly, under its spring pressure, from the shuttle box and, at the same time, withdrawing the filling thread from the shuttle box. Spring loaded members are disposed in sliding engagement with opposed sides of the thread extracting bar, at least one of these spring loaded members having a dull edge to thereby cause one of them to grip the filling thread, as it is pulled past the same by the thread extracting bar, while the other of the spring loaded members has a sharp edge which will sever the filling thread, to thereby permit the exhausted bobbin to be expelled from the shuttle without the possibility of the end of the thread being carried back into the warp upon the next pick.

It is another object of this invention to provide a filling clamp and cutter comprising a support secured to the conventional transfer stud on the magazine of a loom and having a planar base portion, disposed in substantially the same horizontal plane as that of the path of travel of

2
the shuttle at the beat-up point of the lay, and having a thread extracting bar slidably mounted therein. This thread extracting bar is adapted to be used in combination with a shuttle box front having an opening therein which registers with a slot in the shuttle when the shuttle is in boxed position so that the free end of the thread extracting bar may enter the slot in the shuttle, upon a forward or beat-up stroke of the lay, and will thus engage and ensnare the outgoing filling thread which extends across the slots in the shuttle and the shuttle box front, there being means for advancing the thread extracting bar to an operative position upon a substantial exhaustion of the filling thread from a bobbin in the shuttle.

A spring loaded breach pin is adapted to be engaged by the lay upon a forward stroke thereof and this spring loaded pin is mounted for horizontal sliding movement in a relatively small casing or breach pin housing depending, in fixed relation, from the thread extracting bar whereby, upon the lay moving to beat-up position, the breach pin will be depressed to place spring tension upon the bar. The thread extracting bar is held in an operative position by a spring loaded detent and, with continued movement of the lay toward its beat-up position, the spring loaded breach pin will ultimately be depressed to its limit to where movement will be imparted to the thread extracting bar to overcome or "break" the pressure of the spring loaded detent against the bar. Since the bar will have been placed under tension, due to the depression of the spring loaded breach pin associated therewith, immediately upon the effect of the spring loaded detent being overcome by the thread extracting bar, due to movement of the lay toward its beat-up position, the spring loaded pin will induce sudden movement of the bar to cause the same to withdraw from the opening in the shuttle box front pulling the filling thread, with which it has become engaged, outwardly with the same.

It is still another object of this invention to provide, in a thread cutting and clamping device having an automatically releasable thread extracting bar, a spring loaded clamping member which slidably engages the side of the thread extracting bar nearest the selvedge of the cloth being woven and, also, to provide a cutting or severing member which is spring pressed against the opposite side of the thread extracting bar and which slidably engages the bar at a point slightly further from the operating end thereof than the point at which the clamping member

engages the bar, whereby, upon the bar being released, in the manner heretofore described, it will withdraw or extract the filling thread from said opening in the shuttle box front and will cause the yarn to be clamped between the outer wall of the thread extracting bar and the proximate surface of the clamping member and, immediately thereafter, will cause the filling thread to be severed, by virtue of the cutting edge of the severing member being in sliding contact with the opposite surface of the thread extracting bar as the thread extracting bar pulls the filling thread past the severing member.

It is still another object of this invention to provide, in a device of the type described, means automatically operable, following the transfer of a bobbin in the shuttle, for conditioning the thread extracting bar so it may again be advanced to an operative position upon a substantial exhaustion of the filling from a bobbin in the shuttle, said means comprising a pair of intermeshing pinions preferably mounted on a vertical axis on the planar portion of the support, one of the pinions having a bar advancing finger extending therefrom which is provided with a spring loaded cam surfaced thrust pin at the free end thereof, and the thread extracting bar having a follower pin projecting upwardly therefrom which is engageable by the spring loaded cam surfaced thrust pin for advancing the thread extracting bar to an operative position. The conventional transfer mechanism of the loom is adapted to move the free end of the bar advancing finger in an arcuate path past the pin on the bar which will permit the thread extracting bar to be returned to its inoperative position without the necessity of the bar advancing finger on the pinion being returned at the same time.

A connection is provided between the conventional latch depresser stud of the loom and the other of the pinions so that the latch depresser stud, upon being again moved to a normal position following a transfer operation, will cause the thread extracting bar advancing finger to return to its inoperative position, during which time the cam surface on the spring loaded thrust pin will engage the pin projecting from the bar to depress the spring loaded thrust pin as it passes thereby to again position the parts so as to again advance the bar to an operative position upon the filling being exhausted from a succeeding bobbin in the shuttle.

Some of the objects of the invention having been stated, other objects will appear as the description proceeds, when taken in connection with the accompanying drawings, in which—

Figure 1 is a top plan view of the right-hand front portion of a loom showing a portion of the hopper stand of the magazine in cross section and with the lay in a beat-up position and also showing the thread extracting bar advanced to an operative position immediately preceding the transfer of a filled bobbin from the magazine to the shuttle;

Figure 2 is an isometric view of the clamping and cutting device and other parts constituting the invention, but removed from the loom;

Figure 3 is a top plan fragmentary view of the central portion of Figure 1 but showing the parts in a different position;

Figure 4 is an elevation looking at the right-hand side of Figure 1 but showing the improved clamping and cutting device in an operative position and with the lay in a back position and

also omitting the conventional small end disk bobbin holder from the magazine so as to show the conventional transfer mechanism associated therewith;

Figure 5 is an enlarged vertical sectional view taken substantially along the line 5—5 in Figure 1 and showing the spring loaded detent for locking the thread extracting bar in an operative position;

Figure 6 is an elevation looking at the inside surface of the loom side frame member shown in Figure 1 and is taken substantially along the line 6—6 in Figure 1 and showing the breast beam in cross section;

Figure 7 is an enlarged top plan view, of the improved clamping and cutting device, similar to the central portion of Figure 1, but showing the thread extracting bar and actuating means therefor in an inoperative position and also showing the advancing finger partially in longitudinal section;

Figure 8 is an elevation showing the lay, shuttle and shuttle box in cross section and is taken substantially along the line 8—8 in Figure 1;

Figures 9, 10 and 11 are progressive steps in the operation of the thread extracting bar as it moves away from the shuttle box upon extracting a filling thread from the shuttle box;

Figure 12 is an enlarged vertical sectional view through the thread extracting bar, showing the breach pin and associated parts, and is taken substantially along the line 12—12 in Figure 1.

Referring more specifically to the drawings, the numeral 10 indicates the right-hand side frame member of a loom to which is secured, in a conventional manner, one end of a conventional breast beam 11 to which is secured, as by bolts 12, a conventional magazine hopper stand 13. This magazine hopper stand 13, as shown,

is of a type having a rotatable bobbin disk 14 adapted to support the large ends of a plurality of bobbins or quills 15. The magazine shown is of the rotary type, but it is to be understood that any convenient type of magazine will operate equally as well in conjunction with the present invention.

The present invention is shown in association with a loom having a magazine of a type substantially as shown in the patent to Ubald Hebert, Number 1,185,094, of May 30, 1916, and includes a conventional hold back pawl 16 and a feed pawl 17 which cooperates with a ratchet wheel 18 to rotate the bobbin disk 14 a step upon a bobbin in the shuttle, which is being propelled back and forth through the shed of the cloth, becoming substantially exhausted so that the lowermost bobbin therein (Figure 4) will be transferred into the shuttle and at the same time, the exhausted bobbin or quill will be expelled from the shuttle.

The conventional feed pawl 17 is pivotally mounted, as at 20, intermediate the ends of a conventional transfer arm 21 which is oscillatably mounted, at its left-hand end in Figure 4, on the usual transfer stud 22 projecting outwardly from the lower portion of the hopper stand 13. This transfer arm 21 is normally urged upwardly in Figure 4 by the usual torsion spring 23 and also has integral therewith a depending latch pin arm 26 which has an outwardly extending latch pin 27 integral therewith on which is oscillatably mounted a conventional latch finger 29.

Upon the filling thread on a particular bobbin 75 in the shuttle, to be later described, being sub-

stantially exhausted, the latch finger 30 is adapted to be moved upwardly, by means to be later described, to where it will be engaged by a conventional bunter 31, projecting from the front of a lay 32, and will cause the transfer arm 21 to be partially rotated and strike the lowermost quill or bobbin 15 in the magazine, as the lay 32 moves from right to left in Figure 4, to thus effect a transfer operation as the lay 32 reaches its foremost or beat-up position.

The lay 32 is conventional and has disposed on each end thereof a conventional shuttle box, only one of which is shown and comprising a back binder 35 and a conventional box front 36, said box front being secured to a race plate 37 by any suitable means such as bolts 40. This box front 36 has a suitable lining 41, preferably of leather material, which is suitably secured to the side of the box front adjacent the interior of the shuttle box. This lining serves as a wearing surface against which a shuttle 42 slides when it moves to boxed position. The box front 36 and the leather lining have coinciding slots or openings 43 therein and the shuttle 42 also has a slot 44 therein which registers with the slot or opening 43 in the box front 36 when the shuttle 42 is in boxed position.

During normal operation of the loom, the shuttle 42 is adapted to be projected back and forth across the lay 32 of the loom, that is, from one shuttle box to the other, by means of pickers 45 on picker sticks 46, only one of each of which is shown in the drawings. The shuttle 42 has a quill or bobbin 50 therein upon which filling thread or yarn is wound and from this bobbin 50 is a strand of filling thread 51 which passes through the usual shuttle eye, not shown, disposed on the lower side of the shuttle 42 in Figure 1 and from which point this strand of filling thread 51 leads back to the selvedge of the cloth along a groove 52 in the front side of the shuttle 42 (Figure 8).

As the shuttle moves back and forth across the lay, this filling thread 51 gradually unwinds from the bobbin 50 and when substantially all of the filling has been unwound, a suitable detector, not shown, will slip on the substantially empty bobbin 50 and will cause the conventional transfer mechanism to transfer the lowermost bobbin 15 in the bobbin disk 14 (Figure 4) into the shuttle 42, the exhausted bobbin 50 being projected on through the shuttle and through a suitable opening 54 in the bottom of the shuttle box.

The filling detector, not shown, through intervening connections well known to those familiar with the art, and shown in Patent Nos. 1,313,350, of August 19, 1919, and 650,684, of May 29, 1900, and 1,496,640, of June 3, 1924, and 1,392,805, of October 4, 1921, transmits partial counterclockwise rotation to a conventional starting rod 55 (Figures 4 and 8). This starting rod 55 is oscillatably mounted in suitable bearing blocks 56, only one of which is shown in the drawings, and this bearing block 56 is secured, as by bolts 57, to the front vertical surface of the breast beam 11 (Figures 4, 6, 8 and 12). This bearing block 56 also oscillatably supports a conventional shipper shaft 68 which is not pertinent to the present invention.

The breast beam 11 has a slot 62 therein (Figure 6) which is loosely penetrated by a conventional feeler finger 63 fixedly mounted at its right-hand end in Figure 6 on the starting rod 55. This feeler finger 63 has a conventional starting rod spring hook 65 oscillatably mounted

thereon, as at 66, which is normally urged upwardly in Figure 6 against a stop member 67, integral with the feeler finger 63, by a conventional starting rod spring 70. The upper end of the starting rod spring 70 is connected to a tail portion 71 integral with the starting rod spring hook 65 and its lower end is connected, in a conventional manner, not shown, to the side frame 10 of the loom. The free end of the starting rod spring hook 65 has a longitudinally extending slot 74 therein in which a shuttle feeler pin 75 has longitudinal sliding movement.

The pin 75 projects inwardly from a shuttle feeler link 76, the left-hand end thereof in Figure 6 being pivotally connected, as at 77, to a conventional shuttle feeler bracket 80. The shuttle feeler bracket 80 is secured, as by bolts 81 to the inner surface of the loom side frame member 10. The shuttle feeler link 76 has integral therewith a shuttle feeler 83 to which is secured, as by a bolt 84, a conventional shuttle feeler tip 85.

Secured to the shuttle feeler 83, as by a screw 86, is a laterally projecting portion 90 (Figure 1) of a latch depresser 91 having a slot 92 therein, which is penetrated by a bolt 93 for oscillatably connecting the latch finger 30 to the latch depresser 91 (Figures 4 and 8). The latch depresser also has a conventional latch depresser stud 94 projecting outwardly from the free end thereof (Figures 1 and 4). It is thus seen that upon a substantial exhaustion of the filling on the bobbin or quill 50 (Figure 1), partial clockwise movement will be imparted to the starting rod 55, in Figure 6 and will cause the feeler finger 63, along with its starting rod spring hook 65, to partially rotate in a clockwise direction, with the result that the shuttle feeler 83 will thus be caused to move in a counterclockwise direction in Figure 6.

This will, of course, cause the latch depresser 91 to move from the position shown in Figure 4 to substantially the position shown in Figure 8 to cause the free end of the latch finger 30 to be moved to a position where the bunter 31 will strike the same, upon a beat-up stroke of the lay 32, and cause the latch to move forwardly in the manner heretofore described for actuating the transfer arm 21. The parts heretofore described are conventional parts of a loom and it is with these parts that the present invention is adapted to be associated.

The improved filling thread extracting, clamping and cutting device comprises a support broadly designated at 100 and having a boss portion 101 which is fixedly mounted on the conventional transfer stud 22, as by set screws 102. This support 100 has a downwardly extending stem portion 105, in Figures 4 and 8, and also has a planar base portion 106 cast integral with the lower end of the stem 105.

This base portion 106 is disposed in substantially the same horizontal plane as that occupied by the shuttle 42 when the lay 32 is in a beat-up position. The restricted lower ends of vertically disposed stub shafts 110 and 111 are threadably imbedded in the planar base portion 106 of the support 100 and each of these stub shafts 110 and 111 has a screw driver slot 112 therein for tightening the stub shafts 110 and 111 into the planar base portion 106 of the support bracket 100.

The stub shafts 110 and 111 have intermeshing pinions 115 and 116, respectively, oscillatably mounted thereon. Welded to the peripheral surface of the pinion 115, as at 117, is one end of an

arm 120, the free end of which has the restricted upper end 121 of a vertically disposed shoulder screw 122 threadably imbedded therein. The shoulder screw 122 projects downwardly and a substantially horizontally disposed link 123 having a longitudinally extending slot 124 therein is mounted for sliding movement on the shoulder screw 122. The link 123 extends rearwardly and is pivotally connected, as by a screw 125, on a cuff member 126 which is adapted to be slidably mounted on the conventional latch depresser stud 94 as shown in Figures 4, 8 and 12.

Welded to the peripheral surface of the pinion 116, as at 130, is one end of an extracting bar advancing finger 131 having a longitudinally extending bore 132 in the free end thereof (Figure 7) in which a compression spring 133 is mounted. The advancing finger 131 also has coinciding longitudinally extending slots 134 therein for purposes to be presently described.

The compression spring 133 urges a thrust pin 136 outwardly, the thrust pin 136 having a transverse guide pin 137 fixedly mounted therein, as by a pressed fit, and opposed ends of the stop pin 137 have sliding movement in the slots 134 in the extracting bar advancing finger 131. The guide pin 137 not only restricts outward movement of the thrust pin 136 in Figure 7 but also prevents the thrust pin 136 from being rotated in the bore 132 in the end of the bar advancing finger 131.

The leading edge of the thrust pin 136 is preferably flattened or cut away as at 140 (Figure 7), and, upon counterclockwise movement of the bar advancing finger 131 in Figure 7, the surface 140 engages a follower sleeve 141 rotatably mounted on a screw 142 (Figure 12), threadably imbedded in a thread extracting bar 143, for moving the thread extracting bar 143 rearwardly from the position shown in Figure 7 to substantially the position shown in Figures 1, 2 and 12 during a transfer operation.

The thrust pin 136 is also provided with a rounded cam surface 145 disposed on the opposite side of the thrust pin 136 from the flattened surface 140 so when the thread extracting bar 143 has been projected forwardly, or to the position shown in Figure 7, but with the bar advancing finger 131 remaining in substantially the position shown in Figure 1, the bar advancing finger 131 may be partially rotated in a clockwise direction, from the position shown in Figure 1 to the position shown in Figure 7, and, in so doing, the cam surface 145 of the thrust pin 136 will engage the follower sleeve 141 which will cause the thrust pin 136 to partially recede into the bore 132 in the bar 131 so as to move past the follower sleeve 141 and to the position shown in Figure 7.

The planar base portion 106 of the support 100 has a rearwardly projecting portion 146 integral therewith to which the rear end of a cover plate 147, having a slot 150 therein, is secured, as by screws 151. The front end of the cover plate 147 is also secured, as by screws 152, to the upper surface of the planar base portion 106 of the support 100. The planar base portion 106 of the support 100 has a forwardly and rearwardly extending groove 153 cut therein, in which the thread extracting bar 143 has longitudinal sliding movement. The slot 150 in the cover plate 147 is slidably penetrated by the screw 142 and the follower sleeve 141 has longitudinal sliding movement on the upper surface of the cover plate 147. It is thus seen that the screw 142 restricts longitudinal movement of the

thread extracting bar 143, as movement is imparted thereto in opposite directions, by engaging opposite end walls of the slot 150.

Referring to Figure 5, it will be noted that the planar base portion 106 of the support 100 has a bore or cavity 155 therein in which a detent compression spring 156 is mounted and the free end of which normally urges a detent ball 157 outwardly and into the slot 153. The planar base portion 106 of the support 100 also has an access opening 160 therein for inserting the compression spring 156 and the detent ball 157 in the cavity or bore 155. The thread extracting bar 143 has a rounded notch 161 cut in one side, adjacent its lower end in Figure 7, into which the detent ball 157 is urged by the compression spring 156 for locking the thread extracting bar 143 in advanced position for a part of the period during a transfer operation, as will be later described.

The thread extracting bar 143 also has a longitudinally extending rounded bottom groove 162 therein, the left-hand end of which terminates closely adjacent the notch 161 and the other end of which, in Figure 12, terminates substantially midway of the length of the thread extracting bar 143. This groove 162 is provided to accommodate the detent ball 157 during rearward and forward movement of the thread extracting bar 143 and is of such depth that the detent ball 157 will not be forced against the wall of the slot 162 by the compression spring 156 which would resist movement of the thread extracting bar 143.

The bottom wall of the groove 153 has a slot 165 therein (Figure 12) which is adapted to be slidably penetrated by a restricted threaded portion 166 of a breach block 167. This restricted threaded portion 166 is threadably imbedded in a bottomed threaded bore in the lower surface of the thread extracting bar 143. The end wall of the slot 165 in Figure 12 thus restricts movement of the thread extracting bar 143 from right to left when this wall is engaged by the restricted threaded portion 166 of the breach block 167.

The breach block 167 has a forwardly extending horizontally disposed breach pin housing 170 secured therein, as by a set screw 171 (Figures 2 and 12). The breach pin housing 170 has a cavity or longitudinally extending bore 172 therein which is closed at its front end and in which a compression spring 173 is mounted. This compression spring 173 normally urges a headed breach pin 174 rearwardly or outwardly with respect to the opposite side of the breach block 167 from which the breach pin housing 170 extends. The breach pin housing 170 has a pair of coinciding longitudinally extending slots 175 therein which are adapted to be slidably penetrated by opposed ends of a stop or guide pin 176 which penetrates the breach pin 174 and extends outwardly at opposite sides thereof to thus restrict outward movement of the breach pin 174. The guide pin 176 may be secured in the breach pin 174 as by a pressed fit.

As heretofore stated, when the bar advancing finger 131 is partially rotated in a counterclockwise direction in Figures 1, 2 and 7, the thrust pin 145 engages the follower sleeve 141 to thus advance the thread extracting bar 143 to operative position. Now, in order to restrict forward movement of the bar advancing finger 131, there is provided an advancing finger stop pin 180 which projects upwardly from the planar base portion 106 of the support 100 closely adjacent the pinion 116. This advancing finger stop pin 180 may be

secured in the planar base portion 106 of the filling cutter 100, by any suitable means such as a pressed fit, or it may be provided with a restricted threaded lower portion which would be threadably imbedded in the base portion 106.

Now, in order to transmit partial counterclockwise rotation to the bar advancing finger 131, so as to advance the thread extracting bar 143 from the position shown in Figures 4 and 7 to the position shown in Figures 1, 2 and 12, rearward movement of the latch depresser 91, which is caused during a transfer operation, in the manner heretofore described, will cause the latch depresser stud 94 to move rearwardly, as a result of which the front wall of the slot 124 in the link 123 will engage the shoulder screw 120 to transmit partial clockwise rotation to the pinion 115 in Figures 1 and 2.

This will, of course, transmit partial counterclockwise rotation to the pinion 116, along with the bar advancing finger 131, so as to move the same from the position shown in Figure 7 to the position shown in Figures 1 and 2. This will take place at about the time that the lay 32 starts a beat-up stroke and thus the free end of the thread extracting bar 143 will pass through the openings 43 and 44 in the box front 36 and the shuttle 42, respectively, as the beat-up stroke is being completed.

Now, by referring to Figure 12, it will be observed that the free or operating end of the thread extracting bar 143 has a substantially V-shaped notch 182 cut therein and the bar 143 also has a transverse hole 183 therein, the V-shaped notch 182 and the hole 183 being joined by a communicating slot 185, so as to form a hook shaped portion 185a at the thread engaging end of the thread extracting bar 143.

Now, as the thread engaging end of the thread extracting bar 143 moves through the openings 43 and 44 in the box front 36 and the shuttle 42, the filling thread 51, which is drawn reasonably taut across the openings 43 and 44, is engaged by the thread engaging end of the thread extracting bar 143 and the V-shaped notch 182 will guide the filling thread 51 through the slot 185 and thus to the hole 183 where it will be engaged by the hook portion 185a upon reverse movement of the bar 143.

At the same time, and as the lay 32 continues its forward or beat-up stroke, the lay 32 will engage the free end of the breach pin 174 to cause the same to move into the breach pin housing 170 and to place the compression spring 173 under considerable pressure. The lay 32 then pushes the head of the pin 174 against the breach block 167 and thus causes the thread extracting bar 143 to be moved in such a manner as to force the detent ball 157 into the cavity 155 and to thus break the locking effect of the detent ball 157.

Immediately upon this locking effect of the detent ball 157 being broken, the compression spring 173 in the breach pin housing 170 will tend to throw the breach pin housing 170 away from the breach pin, since the head of the breach pin is still in engagement with the front of the lay 32. This will, of course, cause a sudden movement of the thread extracting bar 143 toward the front of the loom at a much faster rate than the rate of movement of the lay 32 in its beat-up stroke, as a result of which the hook 185a formed by the hole 183 and the slot 185 in the thread engaging end of the thread extracting bar 143 will pull or extract the filling thread from within the opening 42.

Now, as the thread extracting bar 143 is caused to move toward the planar base portion 106 of the support 100, opposed sides thereof are engaged by a clamping member 186 and a cutting member 187 which, in the present instance, are shown in the form of leaf spring members, which extend away from the lay and are secured, as by screws 190 and 191, respectively, to opposed sides of the rearwardly projecting portion 146 of the planar base 106. The clamping member 186 and the cutting or severing member 187 may be of any desired construction, the primary requisite being that they are held under spring pressure against opposed sides of the thread extracting bar 143. The cutting member 187 may also be referred to as a blade.

It is obvious that the clamping member 186 should be disposed on the side of the thread extracting bar 143 nearest the loom frame member 10 or the selvedge of the cloth, while the cutting or severing member 187 should be disposed on the side of the thread extracting bar 143 remote from the loom frame member 10. The clamping member 186 should also be disposed slightly nearer the operating end of the thread extracting bar 143 than the cutting or severing member 187.

Referring to Figures 9, 10 and 11 it will be observed that the ends of the clamping member 186 and the cutting or severing member 187 nearest the operating end of the thread extracting bar 143 are beveled as at 193 and 194, respectively. The clamping member 187 is beveled at 193 in such a manner as to tend to guide the filling thread 51, as it is moved, by the hook portion 185a of the bar 143, to a point between the clamping member 186 and the adjacent wall of the thread extracting bar 143, to thus clamp the filling thread 51 as shown in Figure 10.

On the other hand, the operating end of the cutting or severing member 187 is beveled in the opposite manner from the clamping member 186 so as to provide a sharp edge which bears against the adjacent side of the thread extracting bar 143 so that with continued movement of the thread extracting bar 143 past the cutting edge of the cutting or severing member 187 as shown in Figure 11, the cutting member 187 will sever the filling thread 51 as the filling thread 51 is drawn past the cutting edge of the member 187 against the wall of the hook portion 185a of the thread extracting bar 143.

It is thus seen that I have provided an improved filling thread extracting, clamping and cutting device which is not only efficient in its operation but is made up of a substantially lesser number of parts than thread clamping and cutting devices heretofore employed and which will substantially decrease its initial cost of manufacture as well as resulting in a considerable saving to the operator due to the time saved in setting up and adjusting the improved thread clamping and cutting device. It is also more stable and has fewer parts to get out of order and is more positive in its action.

In the drawings and specification there has been set forth a preferred embodiment of the invention, and although specific terms are employed, they are used in a generic and descriptive sense only, and not for purposes of limitation, the scope of the invention being defined in the claims.

I claim:

- An improvement in a filling thread replenishing loom having a lay and a shuttle box at the re-

plenishing side of the loom for receiving a shuttle and the shuttle box having a box front provided with an opening adjacent the thread discharge end of the boxed shuttle, the improvement comprising a thread extracting bar adapted to en-snare the outgoing thread through said opening in the shuttle box front, spring means operable by the lay for suddenly moving the thread extracting bar away from the lay to withdraw the thread from the boxed shuttle, and severing means engaging one side of the thread extracting bar for severing the thread upon the thread extracting bar withdrawing the filling thread from the boxed shuttle, and clamping means engaging the other side of the bar for clamping an extracted thread.

2. An improved thread extracting, clamping and cutting device for use in combination with a filling replenishing loom having a lay and a shuttle box at the replenishing side of the loom for receiving a shuttle having filling thread therein, and the shuttle box having a box front provided with an opening adjacent the thread discharging end of a boxed shuttle, the improved clamping and cutting device comprising a support secured to the loom, a thread extracting bar mounted for sliding movement in the support and being disposed in substantially the same horizontal plane as the shuttle upon a beat-up stroke of the lay, hook means on the thread engaging end of said thread extracting bar for engaging the outgoing thread through said opening in the shuttle box front, means engageable by the lay of the loom for imparting sudden movement to the thread extracting bar in a direction away from the lay of the loom for withdrawing the outgoing thread from the shuttle box, a spring loaded clamping member engaging one side of said thread extracting bar and a spring loaded cutting member engaging the other side of said thread extracting bar whereby, upon movement of the thread extracting bar in a direction away from the lay of the loom, the filling thread will be pulled past the clamping member to be clamped thereby and will also be pulled past the cutting member to be severed thereby.

3. In a filling replenishing loom having a lay and a shuttle box at at least one end of the lay for receiving a shuttle having filling thread therein and said shuttle box having an opening therein coinciding with the path of travel of the filling thread carried by the shuttle, an improved thread extracting device comprising a support, means securing the support to the loom, a thread extracting bar mounted for forward and rearward sliding movement in the support, a pair of intermeshing pinions mounted for oscillation on the support, a connection from one of said pinions to the filling replenishing mechanism of the loom for imparting partial rotation thereto upon the transfer of a bobbin in the shuttle, a thread extracting bar advancing finger projecting from the other of the pinions, a follower on the thread extracting bar engageable by said bar advancing finger for advancing the thread extracting bar to operating position, said thread extracting bar having a hook portion at the operating end thereof adapted to engage and hook the filling thread as it passes through said opening in the shuttle box and means engageable by the lay of the loom for imparting sudden movement to the thread extracting bar in a direction away from the lay of the loom for withdrawing the filling thread from the shuttle box.

4. In a filling replenishing loom having a lay and a shuttle box at at least one end of the lay for receiving a shuttle having filling thread therein and said shuttle box having an opening therein coinciding with the path of travel of the filling thread carried by the shuttle, an improved thread extracting and clamping device comprising a support, means securing the support to the loom, a thread extracting bar mounted for forward and rearward sliding movement in the support, a pair of intermeshing pinions mounted for oscillation on the support, a connection from one of said pinions to the filling replenishing mechanism of the loom for imparting partial rotation thereto upon the transfer of a bobbin in the shuttle, a thread extracting bar advancing finger projecting from the other of the pinions, a follower on the thread extracting bar engageable by said bar advancing finger for advancing the thread extracting bar to operating position, said thread extracting bar having a hook portion at the operating end thereof adapted to engage and hook the filling thread as it passes through said opening in the shuttle box, means engageable by the lay of the loom for imparting sudden movement to the thread extracting bar in a direction away from the lay of the loom for withdrawing the filling thread from the shuttle box, and a spring pressed clamping member engaging the side of the thread extracting bar nearest the end of the lay of the loom whereby, upon the thread extracting bar being moved in a direction away from the lay of the loom, the filling thread will be drawn past said clamping member to be clamped thereby against the side of the thread extracting bar.

5. In a filling replenishing loom having a lay and a shuttle box at at least one end of the lay for receiving a shuttle having filling thread therein and said shuttle box having an opening therein coinciding with the path of travel of the filling thread carried by the shuttle, an improved thread extractor and cutter comprising a support, means securing the support to the loom, a thread extracting bar mounted for forward and rearward sliding movement in the support, a pair of intermeshing pinions mounted for oscillation on the support, a connection from one of said pinions to the filling replenishing mechanism of the loom for imparting partial rotation thereto upon the transfer of a bobbin in the shuttle, a thread extracting bar advancing finger projecting from the other of the pinions, a follower on the thread extracting bar engageable by said bar advancing finger for advancing the thread extracting bar to operating position, said thread extracting bar having a hook portion at the operating end thereof adapted to engage and hook the filling thread as it passes through said opening in the shuttle box, means engageable by the lay of the loom for imparting sudden movement to the thread extracting bar in a direction away from the lay of the loom for withdrawing the filling thread from the shuttle box, and a spring pressed cutter blade engaging the side of the thread extracting bar remote from the end of the lay whereby upon the thread extracting bar being moved in a direction away from the lay of the loom, the thread carried thereby will be drawn past the cutter blade to be severed thereby.

6. In a filling replenishing loom having a lay and a shuttle box at at least one end of the lay for receiving a shuttle having filling thread therein and said shuttle box having an opening

therein coinciding with the path of travel of the filling thread carried by the shuttle, an improved thread cutter comprising a support, means securing the support to the loom, a thread extracting bar mounted for forward and rearward sliding movement in the support, a pair of intermeshing pinions mounted for oscillation on the support, a connection from one of said pinions to the filling replenishing mechanism of the loom for imparting partial rotation thereto upon the transfer of a bobbin in the shuttle, a thread extracting bar advancing finger projecting from the other of the pinions, a follower on the thread extracting bar engageable by said bar advancing finger for advancing the thread extracting bar to operating position, said thread extracting bar having a hook portion at the operating end thereof adapted to engage and hook the filling thread as it passes through said opening in the shuttle box, means engageable by the lay of the loom for imparting sudden movement to the thread extracting bar in a direction away from the lay of the loom for withdrawing the filling thread from the shuttle box, a spring pressed clamping member engaging the side of the thread extracting bar nearest the end of the lay of the loom whereby, upon the thread extracting bar being moved in a direction away from the lay of the loom, the filling thread will be drawn past said clamping member to be clamped thereby against the side of the thread extracting bar, and a spring pressed blade engaging the side of the thread extracting bar remote from the end of the lay whereby, upon the thread extracting bar being moved in a direction away from the lay of the loom, the thread carried thereby will be drawn past the cutter blade to be severed thereby.

7. In a filling replenishing loom having a lay and a shuttle box at at least one end of the lay for receiving a shuttle having filling thread therein and said shuttle box having an opening therein coinciding with the path of travel of the filling thread carried by the shuttle, an improved thread extracting device comprising a support, means securing the support to the loom, a thread extracting bar mounted for forward and rearward sliding movement in the support, a pair of intermeshing pinions mounted for oscillation on the support, a connection from one of said pinions to the filling replenishing mechanism of the loom for imparting partial rotation thereto upon the transfer of a bobbin in the shuttle, a thread extracting bar advancing finger projecting from the other of the pinions, a follower on the thread extracting bar engageable by said bar advancing finger for advancing the thread extracting bar to operating position, said thread extracting bar having a hook portion at the operating end thereof adapted to engage and hook the filling thread as it passes through said opening in the shuttle box and means engageable by the lay of the loom for imparting sudden movement to the thread extracting bar in a direction away from the lay of the loom for withdrawing the filling thread from the shuttle box, said means engageable by the lay for imparting sudden movement to the thread extracting bar in a direction away from the lay of the loom comprising a breach block depending from the thread extracting bar, a spring loaded breach pin mounted for sliding movement in the breach block and adapted to be engaged by the lay of the loom as the lay moves in a beat-up stroke to thereby create an increasing pressure on the breach pin and a spring loaded de-

tent normally holding the thread extracting bar in an advanced position whereby, upon the spring loaded breach pin being moved a predetermined distance by the lay of the loom, the effect of the spring loaded detent, as a holding means for the thread extracting bar, will be overcome and the spring associated with the spring loaded breach pin will impart sudden movement to the breach block and the thread extracting bar in a direction away from the lay of the loom.

8. An improvement in a filling thread replenishing loom having a lay and a shuttle box at the replenishing side of the loom for receiving a shuttle and the shuttle box having a box front provided with an opening adjacent the thread discharge end of the boxed shuttle, the improvement comprising a thread extracting bar adapted to ensnare the outgoing thread through said opening in the shuttle box front, spring means operable by the lay for suddenly moving the thread extracting bar away from the lay to withdraw the thread from the boxed shuttle, severing means engaging one side of the thread extracting bar for severing the thread upon the thread extracting bar withdrawing the filling thread from the boxed shuttle, and clamping means engaging the other side of the bar for clamping an extracted thread, said spring means operable by the lay for suddenly moving the thread extracting bar away from the lay comprising a breach block depending from the thread extracting bar, a spring loaded breach pin mounted for sliding movement in the breach block and adapted to be engaged by the lay of the loom as the lay moves in a beat-up stroke to thereby create an increasing pressure on the breach pin and a spring loaded detent normally holding the thread extracting bar in an advanced position whereby, upon the spring loaded breach pin being moved a predetermined distance by the lay of the loom, the effect of the spring loaded detent, as a holding means for the thread extracting bar, will be overcome and the spring associated with the spring loaded breach pin will impart sudden movement to the breach block and the thread extracting bar in a direction away from the lay of the loom.

9. An improvement in a filling replenishing loom having an oscillatable lay provided with a shuttle box and a battery for holding bobbins having thread thereon and having means for transferring the bobbins from the battery into the shuttle box, said shuttle box having a box front provided with an opening therethrough, said shuttle box being adapted to receive and box a shuttle, said shuttle having a hole through the side thereof coinciding with the hole in the box front when the shuttle is boxed, said improvement comprising a spring pressed thread extracting bar having a hook on its end adjacent the shuttle box for passing through the holes in the box front and the shuttle for ensnaring a thread on a bobbin about to be transferred and having means engageable by the lay of the loom for releasing the spring pressed means to quickly withdraw the thread extracting bar from the shuttle box, a clamping means slidably engaging that side of the thread extracting bar adjacent the edge of the cloth being woven and having a cutter member engaging the opposite side of the thread extracting bar for severing the thread which is extracted from the shuttle box by the thread extracting bar.

10. In a loom having an oscillatable lay provided with a shuttle box on one end thereof and having a filling replenishing mechanism, said

shuttle box being adapted to receive and box a shuttle having thread therein and having a box front on one side thereof provided with an opening and the shuttle having an opening coinciding with the opening in the box front when the shuttle is boxed, combined thread extracting, clamping and severing means comprising a thread extracting bar slidably mounted on the loom and adapted to pass through the holes in the shuttle box front and the shuttle upon a beat-up motion of the lay, said thread extracting bar having tension means normally tending to move it away from the shuttle box and having a detent for holding it in extended position when it passes through the holes in the shuttle box front and the shuttle, detent releasing means engageable by the oscillating lay upon a beat-up motion to unlatch the thread extracting bar to allow its tension means to quickly withdraw the thread extracting bar from the shuttle box, said thread extracting bar having a hooked portion adapted to ensnare the thread and withdraw it through the opening in the box front, and said thread extracting bar having clamping and cutting means associated therewith adapted to engage the thread upon the tension means returning the thread extracting bar to normal position.

11. In a filling replenishing loom having a lay and a shuttle box at at least one end of the lay for receiving a shuttle having filling thread therein and said shuttle box having an opening therein coinciding with the path of travel of the filling thread carried by the shuttle, an improved thread cutter comprising a support, means securing the support to the loom, a thread extracting bar mounted for forward and rearwardly sliding movement in the support, a pair of intermeshing pinions mounted for oscillation on the support, a connection from one of said pinions to the filling replenishing mechanism of the loom for imparting partial rotation thereto upon the transfer of a bobbin in the shuttle, a thread extracting bar advancing finger projecting from the other of the

pinions, a follower on the thread extracting bar engageable by said bar advancing finger for advancing the thread extracting bar to operating position, said thread extracting bar having a hook portion at the operating end thereof adapted to engage and hook the filling thread as it passes through said opening in the shuttle box and means engageable by the lay of the loom for imparting sudden movement to the thread extracting bar in a direction away from the lay of the loom for withdrawing the filling thread from the shuttle box, a thrust pin mounted for longitudinal sliding movement in the free end of the bar advancing finger, spring means normally urging said thrust pin outwardly with respect to the bar advancing and said thrust pin having a cam surface on the side thereof remote from the operating end of the thread extracting bar whereby, upon movement being imparted to the bar advancing finger in a direction toward the operating end of the thread extracting bar, the thrust pin will engage the follower associated with the thread extracting bar for advancing the thread extracting bar to an operating position and, upon movement of the bar advancing finger in a direction away from the operating end of the thread extracting bar, following movement of the thread extracting bar in a direction away from the lay of the loom, the cam surface on the thrust pin will engage the follower associated with the thread extracting bar and will recede into the bar advancing finger so as to move past the follower associated with the thread extracting bar.
